CLAIM

The ornamental design for a children's swivel chair, as shown and described.

DESCRIPTION

FIG. 1 is a front, top, right perspective view of a children's swivel chair showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, bottom, left perspective view thereof.

The broken lines represent portions of the children's swivel chair that form no part of the claimed design.
